UNITED STATES PATENT OFFICE.

FARRINGTON DANIELS, OF MADISON, WISCONSIN.

DETERGENT COMPOSITION.

No Drawing.

Application filed October 16, 1925. Serial No. 62,937.

The present invention relates to improvements in detergent compositions and will be fully understood from the following description thereof, in which illustrative examples 5 of compositions made in accordance with this invention are given.

In accordance with this invention, a detergent composition is prepared by admixing an alkali metal phosphate having an alkaline 10 reaction with an oily vehicle containing a fatty acid compound. As alkaline metal phosphates I include the phosphates of the various members of the alkali metal series including ammonium and substituted ammonium derivatives); for example, the di- and tri-substituted phosphates of sodium, 15 potassium, ammonium, tetramethyl ammonium, and the like; and also the mixed phosphates, such as ammonium sodium hydrogen phosphate, sodium potassium hydrogen phosphate, potassium ammonium hydrogen phosphate, sodium potassium ammonium phosphate and the like. I prefer to employ the di-sodium or tri-sodium phosphates.

25 The oily vehicle with which I admix the alkaline alkali metal phosphate compound is one which preferably includes a fatty acid compound such as a fatty acid, or an ester of a fatty acid although the detergent action of 30 the composition may be secured without the presence of such a compound. The vehicle also includes an oily substance capable of mixing with ordinary grease or oil, as normally present in dirt to be removed by such 35 detergent compositions. Thus I may employ ordinary fatty oils derived from animal, or vegetable sources, in which the oily vehicle inherently includes the fatty acid compound. I may likewise employ hydrocarbon oils in the 40 oily vehicle, either alone or with a fatty acid compound.

The precise proportions in which the constituents of the detergent mixture are mixed is not material. In general I prefer that the 45 proportion of the solid phosphate constituent shall be such as to produce a pasty mass, which, for example, may be a fairly stiff paste if it is desired to dispense the product in the form of a mechanic soap or paste in cans, or 50 may be a somewhat more fluid paste if it is de-

sired to dispense the product in tubes. A suitable mixture, for example, is one containing 50 to 60 parts of the solid phosphate in granulated or finely powdered form and 20 to 30 parts by weight of the oily constituent. 55 These proportions may be widely varied, according to the nature of the constituent and the consistency desired. My preferred mixture is one containing tri-sodium phosphate and an oil such as cottonseed oil, olive oil, or 60 corn oil. The mixture may be moderately heated, if desired, although such heating is unnecessary.

In preparing the mixture I may also add a small proportion, say 1 to 5% of palm oil, 65 which appears to stabilize the composition, tending to prevent separation of its constituents. Thus a suitable specific mixture is 50 parts tri-sodium phosphate; 30 parts cottonseed oil and 1 part palm oil. 70

No substantial chemical reaction takes place; in fact, in general no chemical reaction is detectable except, perhaps, on long standing of the composition. In use, the mixture is preferably employed as a detergent composition, for example, by thoroughly rubbing it upon or into the parts to be cleansed with a minimum amount of water and subsequently removing the composition by rinsing with more water. It is believed that, in the 80 initial application of the detergent composition, in which small amounts of water are present, a sufficient saponification of fats or oils present in the composition itself or in the dirt to be removed occurs to produce an emulsifying agent and permits the formation of a water and oil emulsion, the oily portion of the vehicle of the composition causing it to thoroughly interpenetrate the dirt particles. In subsequent rinsing an oil-in-water emulsion is formed, which is readily removed by 85 water. I have found that, in the use of such compositions upon the skin, the natural oils of the skin are protected from the action of the strong alkaline solution of phosphate and there is uniformly left a thin, imperceptible oil film which prevents drying out and chapping of the skin. 90

I claim:

1. A detergent composition comprising an 100

alkaline alkali metal phosphate and an oily vehicle including a fatty acid compound of the class consisting of the fatty acids and their glycerides, said composition being substantially free of soaps.

2. A detergent composition comprising 50 to 60 parts of tri-sodium phosphate and about 20 to 30 parts of a vegetable oil.

3. A detergent composition consisting of

fatty oil and trisodium phosphate dispersed therein and substantially free of soaps.

4. A detergent composition comprising 50 to 60 parts of trisodium phosphate and about 20 to 30 parts of a vegetable oil, said composition containing a minor proportion of palm oil.
